(57) **CLAIM**

The ornamental design for an electric bicycle as shown and described.

DESCRIPTION

FIG. 1 is a top-front-left side perspective view of an electric bicycle embodying my new design;

FIG. 2 is a top-rear-right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged and partial perspective view of area 9 in FIG. 2; and,

FIG. 10 is an enlarged and partial perspective view of area 10 in FIG. 2.

The broken lines in the drawings depict portions of the electric bicycle that form no part of the claimed design. The dot-dash broken lines in drawings are provided for annotative purposes to graphically indicate the areas of enlargement. The dot-dash broken lines do not represent actual structure and do not form part of the claimed design.
